UNITED STATES PATENT OFFICE.

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

REVOKING MEANS FOR REGULARLY-ACTUATED TRANSFERRER MECHANISM.

Application filed December 22, 1926. Serial No. 156,476.

This invention relates to improvements in revoking mechanism for weft replenishing looms, and it is the general object of the invention to provide a simple means for preventing the downward movement of a regularly moving transerrer arm should the shuttle be misplaced on the transfer pick of the loom.

In looms of the type set forth in patent to Ryon #1,372,316, the transerrer is given a regular downward movement on alternate beats of the loom to present a weft detecting mechanism through the top of the shuttle box. When such a construction is employed on multi-color weft replenishing looms, it is desirable not only to prevent transfer when the active shuttle is misplaced, but also to release the untransferred bobbin so as to avoid confusion of colors in the pattern. In my application, No. 155,741, I have shown a pair of actuators, one of which is operative under normal conditions to move the transerrer down while the loom is on front center and the other of which acts when the shuttle is improperly placed to bring the transerrer down at a later time in the cycle of the pick to expel the untransferred bobbin while the lay is in its rear position. It is an important object of my present invention to avoid the use of a double actuator and substitute therefor a single actuator which may be disconnected from the transerrer arm by means of a shuttle feeler.

It is a further object of my present invention to provide bobbin supports for the mechanism which shall normally be in bobbin supporting position but one of which is arranged to move to bobbin releasing position every time the actuator is disconnected from the transerrer arm.

It is a still further object of my present invention to provide a yieldable bobbin support and to give the same a bobbin releasing movement only at such times as the shuttle is misplaced.

With these and other objects which will appear as the description proceeds, my invention relates to the arrangements and combinations of parts hereinafter set forth, and more particularly pointed out in the claims.

In the accompanying drawings, wherein a convenient embodiment of my invention is shown:

Fig. 1 is a side elevation of part of a weft

replenishing mechanism viewed from the interior of the loom and showing the parts in normal position prior to a transferring movement, with the shuttle properly placed,

Fig. 2 is a view similar to Fig. 1 but with the transerrer arm disconnected from its actuator and the shuttle misplaced,

Fig. 3 is a horizontal section on line 3—3 of Fig. 2,

Fig. 4 is a view similar to Fig. 1, parts being omitted and showing the actuator in the position it assumes on its upward movement after the time normally allowed for a transfer,

Fig. 5 is a view similar to Fig. 4 but with the actuator shown connected to the bobbin support to move the same to bobbin releasing position, and

Fig. 6 is a detailed horizontal section on line 6—6 of Fig. 1.

Referring to the drawings, I have provided a frame 10 on which is mounted a multi-color weft replenishing mechanism 11 having a transerrer arm 12 pivoted thereto at 13. Vertically reciprocating actuator rod 14 is given a downward motion on each pick of the loom when the shuttle is under the weft replenishing magazine and normally acts to move the transerrer arm downwardly when the lay L is in forward position. This rod 14 is similar to the one set forth in the aforesaid patent to Ryon and has an upward movement immediately following its downward movement so as to carry the detector supported on the transerrer arm above the lay before the latter moves to its rear position.

My improvements include a bobbin support 20 pivoted on a cross rod 21 on the magazine and constrained to move in a right hand direction about the rod 21 by means of a torsion spring 22 one end of which engages a fixed structure, as at 23 and the other end of which engages the support as at 24. A set screw 25 in the support engages a portion of the mechanism frame to limit movement of said support. A second support 26 forming no part of my present invention and being of the usual form may be provided for the other side of the bobbin.

As shown more particularly in Fig. 6, the support 20 has an offset arm 27 in which is secured a stud 28 on which is pivoted a trip 29. Said trip has a finger 30 extending to

the left as shown in Fig. 4 and has the opposite side thereof connected to one end of a tension spring 31 the other end of which is secured to the support 20. The normal function of spring 31 is to hold the finger 30 in position shown in Figs. 1 and 4 so that the end of the finger is below the stud 28.

The rod 14 is formed at the upper end thereof with the head 40 having a pocket 41 which is normally occupied by a boss 42 rigid with the transferrer arm 12 said boss being preferably formed as part of a stud 43 secured to the transferrer arm. The upper end of the head 40 has a notch defined by a vertical wall 44 and a horizontal wall 45 and positioned to cooperate with the finger 30 in a manner to be described hereinafter.

The transferrer arm is extended forwardly of its pivot 13 as at 50 and has a stud 51 normally lying in the bottom of a slot 52 formed in rod head 53 on the lower end of rod 54. Said rod is guided in a boss 55 fixed with respect to the magazine and a compression spring 56 interposed between the boss and head 53 tends to hold the rod in lower position. Said spring not only tends to quicken an upward movement of the transferrer arm after the downward movement thereof so that the detector may clear the lay as set forth in application to Chevrette Serial No. 16,749, but it also holds the transferrer in the position shown in Fig. 2 when the same is disconnected.

The devices to determine when rod 14 shall be disconnected from the transferrer arm include a shuttle feeler having a nose 60 positioned normally to be engaged by a misplaced shuttle, said nose being perforated as at 61 to have the rod 14 pass therethrough for free vertical reciprocation. The forwardly projecting shank 62 of the feeler is guided in a bearing member 63 and a compression spring 64 interposed between the nose 60 and the bearing 63 holds the shuttle feeler in rearward position normally with the head 40 of the rod in engagement with the lug 42.

Under normal conditions the tip of a properly placed shuttle will be out of alignment with the nose 60 and the parts will remain in the position shown in Fig. 1 when the lay advances. As the lay nears its extreme forward position rod 14 will be given a quick downward motion by mechanism not shown herein but similar to that set forth in said patent to Ryon. Immediately after the downward movement the rod will move upwardly and will be held by spring 64 so that the head 40 and more particularly the horizontal wall 45 will move to one side of the finger 30. The support 20 will therefore remain unmoved.

When the shuttle is misplaced, however, it will engage the nose 60 as the lay moves forwardly, compressing spring 64 and mov-

ing the rod 14 forwardly to cause pocket 41 to move out of registry with lug 42 as in Fig. 2. Head 40 thereupon engages finger 30 to move the same in a counterclockwise direction, but as spring 31 is weaker than spring 22 the support 20 will remain at rest to support the bobbin B in transfer position. The transferrer arm then falls until stud 51 is arrested by rod 54 and spring 56 and actuator rod 14 descends without the transferrer arm. During the downward movement of the rod 14 the end of finger 30 will move over the horizontal wall 45 to the position shown in Fig. 4. As the rod 14 moves upwardly the finger 30 will be moved in a clockwise direction by the horizontal face 45 until engaged by the vertical wall 44. Because of the fact that the bottom of finger 30 is below stud 28, continued upward movement of rod 14 will move stud 28 to the right from the position shown in Fig. 4 to that shown in Fig. 5. This is accompanied by a movement of the support 20 to the right of the bobbin so that the latter is released and may fall. At this time the lay is moving backwardly as set forth in Ryon Patent #1,872,316 and the bobbin falls free of the lay.

In the normal operation of the loom, upward movement of the rod 14 is not completed until after the lay has moved rearwardly so that the nose 60 will be disengaged from the shuttle, but this will not interfere with the bobbin releasing movement of the support inasmuch as lug 42 holds head 40 in the position shown in Fig. 4 during the upward movement of said rod 14. During the upward movement of rod 14 the pocket 41 will come to a position to receive lug 42 and spring 64 will immediately move the head 40 to the left from the position shown in Fig. 5 to that shown in Fig. 1. In this way normal driving engagement of the rod and transferrer arm is reestablished.

From the foregoing it will be seen that I have provided means whereby a regularly moving transferrer arm 12 will be prevented from completing its downward movement when a shuttle is misplaced. It will further be seen that means are provided for moving the bobbin support to release the bobbin when transferrer is revoked. It will further be seen that the bobbin support is given a releasing movement only at such times as the shuttle is misplaced. Also means are provided for holding the transferrer arm in raised position when disconnected from rod 14 so that the untransferred bobbin will not be expelled from the magazine when the lay is in forward position.

Having thus described my invention it will be apparent that changes and modifications may be made therein by those skilled in the art without departing from the spirit and scope of the invention and I do not wish to

be limited to the details herein disclosed but what I claim is:

1. In a weft replenishing loom having a transferrer arm and a shuttle, means to give 5 the transferrer arm a regular periodic movement toward the shuttle, and means effective during continued operation of the loom to disconnect the transferrer arm from the first named means to prevent said movement of 10 the transferrer arm toward the shuttle when the shuttle is misplaced.

2. In a weft replenishing loom having a transferrer arm and a shuttle, a regularly moving member normally connected to the 15 transferrer arm to give the latter a movement toward the shuttle at periodic intervals, and devices to disconnect the means from the transferrer arm when the shuttle is misplaced to prevent movement of the trans- 20 ferrer arm toward the shuttle.

3. In a weft replenishing loom having a transferrer arm and a shuttle, a shuttle feeler to be engaged by a misplaced shuttle, means 25 normally connected to the transferrer arm to give the latter a regular periodic movement toward the shuttle, said means being detachable from the transferrer arm and connected to the shuttle feeler and movable by the latter when the shuttle is misplaced to be dis- 30 connected from the transferrer arm and have an idle movement relatively to the latter.

4. In a weft replenishing loom having a transferrer arm and a shuttle, a shuttle feeler 35 to be engaged by a misplaced shuttle, regularly moving mechanism normally having driving relation with respect to the trans- ferrer arm but disconnectible therefrom, said shuttle feeler controlling the position 40 of the means and moving the latter out of driving engagement with the transferrer arm when the shuttle is misplaced.

5. In a weft replenishing loom, a trans- 45 ferrer arm, regularly moving means normally effective to give the transferrer arm a transferring movement, and a shuttle feeler controlling the means to render said means ineffective to give the transferrer arm a transferring movement when the shuttle is 50 misplaced.

6. In a weft replenishing mechanism hav- 55 ing a transferrer arm and a bobbin to be transferred into a shuttle, means to give the transferrer arm a regular movement at periodic intervals, detachable connections be- 60 tween the means and the transferrer arm, a yieldable bobbin support to hold the bobbin in transferring position, and connections be- 65 tween the means and the support, said con- nections being effective to move the support to bobbin releasing position when said means is disconnected from the transferrer arm.

7. In a weft replenishing mechanism hav- 65 ing a transferrer arm and a bobbin to be transferred into a shuttle, regularly mov-

ing means normally connected to but de- 70 tachable from the transferrer arm, a shuttle feeler to be engaged by a misplaced shuttle and controlling the means, a yieldable bob- 75 bin support to hold a bobbin in transfer position, and connections between the means and the support, said shuttle feeler being effective to disconnect the means from the transferrer arm when the shuttle is mis- placed, said connections at this time being 80 effective to cause the support to have a bobbin releasing position.

8. In a weft replenishing mechanism hav- 85 ing a transferrer arm and a bobbin to be transferred into a shuttle, means to give the 90 transferrer arm a regular transferring move- ment, a yieldable bobbin support to hold a bobbin in transfer position, and mechanism controlled by a misplaced shuttle to discon- 95 nect the means from the transferrer arm and establish connection between said means and the support to give the latter a bobbin releasing movement.

9. In a weft replenishing loom, a trans- 95 ferring member, a bobbin supporting mem- 100 ber to hold the bobbin in transfer position, a regularly reciprocating device normally having contact with the transferring mem- 105 ber and being out of relation with respect to the supporting member, and means con- 110 trolled by a misplaced shuttle to disconnect the device from the transferring member and establish operative relation with respect to said device and the supporting member to give the latter a bobbin releasing move- 115 ment.

10. In a weft replenishing mechanism, a transfer member, a bobbin supporting mem- 120 ber, and a regularly moving controlled de- 125 vice to have operative contact with one of said members at a time, said device normally connected to the transfer member and disconnected from the support member but being disconnected from the transfer member and operatively related to the supporting member to give the latter a bobbin releasing position when the shuttle is misplaced.

11. In a weft replenishing mechanism, a transfer member, a bobbin supporting mem- 125 ber, a regularly reciprocating device to have 130 operative contact with one of said members at a time and having engagement normally with the transfer member, and means de- 135 pending upon the position of the shuttle and effective when the shuttle is misplaced to shift said device from operative relation with respect to the transfer member to op- 140 erative relation with respect to the support member to give the latter a bobbin releas- 145 ing movement.

12. In a weft replenishing mechanism, a pair of members one of which effects trans- 150 fer and the other of which supports a bobbin in transfer position, a regularly mov- 155 ing actuator to have operative relation with

but one of said members at a time, and means dependent upon the shuttle to determine which of said members shall be operatively related to the actuator.

- 5 13. In a weft replenishing mechanism, a transerrer arm, a regularly moving actuator therefor, means to disconnect the transerrer from the actuator when a shuttle is misplaced, and means to hold the transerrer arm in raised position during the time that the actuator has the movement which would normally be effective to transfer.
- 10 14. In a weft replenishing mechanism, a pair of members one of which is effective to transfer a bobbin and the other of which is effective to hold the bobbin in transfer position, a regularly moving actuator, means
- 15

dependent upon the position of the shuttle to determine which of said members shall be operatively related to the actuator, and means to support the transferring member when the actuator is disconnected therefrom and operatively related to the supporting member.

15. In a weft replenishing mechanism, a transerrer arm, a regularly moving actuator therefor normally connected thereto, means to disconnect the actuator from the arm when a shuttle is misplaced, and means to support the transerrer arm when the actuator is disconnected therefrom.

In testimony whereof I have hereunto affixed my signature.

OSCAR V. PAYNE.
